United States Patent [19]

Bengtson

[11] Patent Number: Des. 278,316

[45] Date of Patent: ** Apr. 9, 1985

[54] FLOWMETER FLOW TUBE

[75] Inventor: **Darroll D. Bengtson**, New Brighton, Minn.

[73] Assignee: **Rosemount Inc.**, Eden Prairie, Minn.

[**] Term: **14 Years**

[21] Appl. No.: **401,889**

[22] Filed: **Jul. 26, 1982**

[52] U.S. Cl. **D10/96**

[58] Field of Search D10/100; 73/273, 431,
73/861.12

[57] CLAIM

The ornamental design for a flowmeter flow tube, substantially as shown and described.

DESCRIPTION

FIG. 1 is a perspective view of a flowmeter tube embodying my new design;

FIG. 2 is an end elevational view thereof;

FIG. 3 is a top plan view thereof;

FIG. 4 is a bottom plan view thereof; and

FIG. 5 is a side elevational view thereof; and

FIG. 6 is a side elevational view thereof as viewed from the side opposite FIG. 5; the end view not shown is a mirror image of the end view shown.

Fig. 1
